UNITED STATES PATENT OFFICE.

ADELAIDE TAYLOR, OF STEVENS POINT, WISCONSIN.

HAT-BOX.

1,154,457.

Specification of Letters Patent. Patented Sept. 21, 1915.

Application filed May 6, 1915. Serial No. 26,348.

To all whom it may concern:

Be it known that I, ADELAIDE TAYLOR, a citizen of the United States, residing at Stevens Point, in the county of Portage and State of Wisconsin, have invented certain new and useful Improvements in Hat-Boxes; and I do declare the following to be a full, clear, and exact description of the invention, such as will enable others skilled in the art to which it appertains to make and use the same.

This invention relates to improvements in boxes and more particularly to hat boxes.

The object of the invention is to provide a simply constructed, cheap and efficient box of this character such as is used by milliners on their shelves and in which the hats may be kept free from dust and in such a manner as to preserve their shapes and yet render them readily accessible to facilitate the handling of the stock without necessitating the handling of the boxes.

Another object of the invention is to provide a box of this character provided at one side with doors to enable the contents of the box to be removed without necessitating removal of the lid at the top of the box.

Another and more specific object is to provide a hat box that is formed of cardboard or the like and consists of a rectangular body having a flanged and removable lid and hinged doors in one side wall so as to be easily opened and moved into closed position.

Another object of importance is to provide a hat box of the character described which may be opened on the side to enable storing of a large number of boxes one upon the other in such a manner that a person may readily remove the contents of any one of the boxes without having to lift the boxes off one another to remove the lid.

With these and other objects in view, the invention consists of certain novel features of construction, and the combination and arrangement of parts as will be more fully described and claimed.

In the accompanying drawings: Figure 1 represents a perspective view of a hat box constructed in accordance with this invention and shown in closed position; Fig. 2 is a front elevation thereof with the doors in open position; Fig. 3 is a plan view thereof with the top removed; Fig. 4 is a vertical central section taken on the line 4—4 of Fig. 2; Fig. 5 is a plan view of the blank from which the box is constructed; Fig. 6 is a

similar view of the blank from which the lid is constructed; and Fig. 7 is a detail perspective view of the front reinforcing member.

In the embodiment illustrated a box 1 is shown which may be either rectangular or square as desired, being here shown square, and which is composed of heavy cardboard or other suitable material, the blank from which it is formed being of the shape shown in Fig. 5 and comprising a bottom 2 having side members 3, 4 and 5 hingedly connected to three side edges thereof, and a lip 6 designed to extend upwardly from the other side edge of said bottom. The side 4 is substantially of the same size and shape as the bottom 2. The sides 3 and 5 are provided at the rear side edges thereof with flaps 7 and 8 here shown of the same size and configuration as the side member 4 and which are designed to overlap said side member and each other when the box is assembled as shown in Fig. 4, thus forming three thicknesses at the rear of the box, said flaps and member 4 being connected in any suitable manner, preferably by means of clips 9 which connect the upper edges thereof and the lower edge of the overlapping outside flap 7 may be secured by stapling, gluing, or in any other suitable manner.

Connected with the front side edges of the members 3 and 5 are two doors 10 and 11 which extend from the lower edge or bottom of said side members to a point near the top thereof, and when closed are designed to slightly overlap at their edges to provide an efficient closure at this side of the box, in which position they are retained by means of tapes 12 which are secured intermediately of their ends to the side members 3 and 5, said tapes being here shown passed through aligned apertures 13 in said side members and secured to said members by staples 14 or any other suitable means so that one end of each tape extends forwardly in position to be passed across the doors 10 and 11 and tied for securely holding these doors in closed position. The other ends of the tape are made of sufficient length to extend upwardly over the box for securing the top 20 thereto as will be hereinafter more fully described.

Extending from the upper portion of the side edges of the members 3 and 5 are two strips 15 and 16 which are of the same length as the width of the side members 3 and 5

and are designed to be disposed in overlapping relation as shown in Fig. 3 and secured together by any suitable means, clips 17 being shown for this purpose and which also 5 connect a reinforcing member 18 shown disposed on the inner face of the overlapping strips 15 and 16 and which is preferably made of a width greater than the width of said strips although not necessarily so, the 10 additional width of said reinforcing strip extending below the lower edges of the strips 15 and 16 and forming a stop or abutment 19 against which the doors 10 and 11 are designed to close. This reinforcing strip 18 is shown provided at its opposite ends with 15 right angular inwardly extending arms 18' which lie against the inner faces of the sides 3 and 5 and serve to reinforce the corners of the tops where the strips 15 and 16 join 20 said sides 3 and 5.

The lip 6 which is secured to the bottom 2 in a plane below the strips 15 and 16 forms a stop for the lower ends of the doors to prevent them from being forced into the 25 box should pressure be exerted thereon.

The top 20 is shown of a shape to conform to the shape of the box to which it is to be applied and is provided on its side edges with depending flanges 21 and 22, the flanges 30 22 on opposed sides of the top being of a length corresponding to the width of the top, while the flanges 21 on the two other sides of the top are of a length greater than the width of the top providing flaps 23 at 35 the ends thereof which are designed to overlap the adjacent ends of the flanges 22 and to be secured thereto in any suitable manner, clips 24 being here shown for this purpose, although obviously they may be glued 40 if found more desirable. When this top has been set up with these flanges arranged at right angles and the flaps 23 secured in operative position, it is ready to be placed on the box with the flanges thereof shut down 45 over the side edges of the box and thus completely closing it at its upper end. When so positioned, this top is held against accidental removal by means of the free ends of the tapes 12 which extend across said top 50 20 and are tied at the center thereof in the usual manner.

From the above description it will be obvious that these boxes with the tops secured in position thereon by the tapes referred to 55 may be placed one upon the other on shelves or otherwise with the doors 10 and 11 disposed outwardly so that when access to the box is desired all that is necessary is to untie the ends of the tapes which secure the doors 60 and said doors may be readily opened to permit the contents to be removed and replaced whenever desired.

I claim as my invention:

1. A hat box comprising a bottom wall, 65 side walls secured to three of the edges of

the bottom wall, a lip secured to the other edge thereof and extended upward to form a door stop, doors hingedly connected to the free ends of two of said side walls, said doors being of a height less than the height 70 of said side walls, a strip connecting said side walls above said doors, a stop extending below said strip and a closure for the upper end of said box.

2. A hat box comprising a bottom wall, 75 side walls secured to three of the edges of the bottom wall, a lip secured to the other edge thereof, doors hingedly connected to the free ends of two of said side walls, said doors being of a height less than the height 80 of said side walls, a strip connecting said side walls above said doors, a removable top for closing the upper end of said box, and a reinforcing strip secured to the inner face of said cross bar and extending below said 85 cross bar to form a stop for said doors at the upper ends thereof, the lip secured to said bottom forming a stop for the lower end thereof.

3. A hat box consisting of a bottom wall, 90 side walls secured to three of the edges of said bottom wall and separated from each other, two of said side walls being provided at one end with overlapping flaps adapted to overlap each other and the other side 95 wall of the box to form a reinforced wall of triple thickness, doors hinged at one side to the free edges of said sides and adapted to close the open side of said box, said doors being of less height than said sides to which 100 they are connected terminating short of the upper ends thereof, and a connecting strip arranged between said sides above said doors.

4. A hat box consisting of a bottom wall, 105 side walls secured to three of the edges of said bottom wall and separated from each other, two of said side walls being provided at one end with overlapping flaps adapted to overlap each other and the other side wall 110 of the box to form a reinforcing wall, doors hinged at one side of the free edges of said flap carrying sides and adapted to close the open side of said box, said doors being of less height than said sides to which they are 115 connected terminating short of the upper ends thereof, a connecting strip arranged between said sides above said doors, and a reinforcing strip for said connecting strip arranged on the inner face thereof and having right angularly extending arms at its opposite ends positioned to engage the inner faces of the sides to which the doors are connected.

5. A hat box consisting of a bottom wall, 125 side walls secured to three of the edges of said bottom wall and separated from each other, two of said side walls being provided at one end with overlapping flaps adapted to overlap each other and the other side 130

- wall of the box to form a reinforcing wall, doors hinged at one side to the free edges of said flap carrying sides and adapted to close the open side of said box, said doors being of less height than said sides to which they are connected terminating short of the upper ends thereof, a connecting strip arranged between said sides above said doors, and a reinforcing strip for said connecting strip arranged on the inner face thereof and having right angularly extending arms at its opposite ends positioned to engage the inner faces of the sides to which the doors are connected, said reinforcing strip being wider than the strip with which it is connected with the lower edge extending below the lower edge of said connecting strip to form an abutment for said doors at their upper ends, an upstanding lip on the free edge of said bottom over which said doors are designed to lap to form an abutment at the bottom of the box for said doors, and means for holding said doors in closed position. 5
6. A hat box consisting of a bottom wall, side walls secured to three of the edges of said bottom wall, and separated from each other, two of said side walls being provided at one end with overlapping flaps adapted to overlap each other and the other side wall of the box to form a reinforcing wall, doors hinged at one side to the free edges of said flap carrying sides and adapted to close the open side of said box, said doors being of less height than said sides to which they are connected terminating short of the upper ends thereof, a connecting strip arranged between said sides above said doors, a reinforcing strip for said connecting strip arranged on the inner face thereof and hav- 10 15 20 25 30
- ing right angularly extending arms at its opposite ends positioned to engage the inner faces of the sides to which the doors are connected, said reinforcing strip being wider than the strip with which it is connected with the lower edge extending below the lower edge of said connecting strip to form an abutment for said doors at their upper ends, an upstanding lip on the free edge of said bottom over which said doors are designed to lap to form an abutment at the bottom of the box for said doors, and means for holding said doors in closed position. 35 40 45
7. A hat box having a removable top and hinged doors at one side thereof, tapes secured intermediately of their ends to two of the opposed side walls of said box, the ends of said tapes extending in planes at right angles to each other, two of the ends of said tapes being designed to pass over the doors at the side of the boxes and be secured together for holding said doors in closed position, and the other ends of said tapes being adapted to pass over the top of the box and secured for holding the top in closed position. 50 55 60
- In testimony whereof I have hereunto set my hand in presence of two subscribing witnesses.
